UNITED STATES PATENT OFFICE.

THOMAS G. HAWKES, OF CORNING, NEW YORK.

DESIGN FOR A GLASS VESSEL.

No. 40,195.

Specification for Design.

Patented Aug. 3, 1909.

Application filed April 7, 1909. Serial No. 488,533. Term of patent 7 years.

To all whom it may concern:

Be it known that I, THOMAS G. HAWKES, a citizen of the United States, residing at Corning, in the county of Steuben, State of New York, have invented a new, original, and ornamental Design for a Glass Vessel, of which the following is a specification, reference being had to the accompanying drawing, forming part thereof.

The figure is a plan view of a glass vessel showing my design.

I claim:

The ornamental design for glass vessel, as shown.

THOMAS G. HAWKES.
